UNITED STATES PATENT OFFICE

2,003,341

UNDERFRAME CONSTRUCTION FOR
RAILWAY CARS

Argyle Campbell, Chicago, Ill., assignor to Enterprise Railway Equipment Company, Chicago, Ill., a corporation of Illinois

Application April 13, 1933, Serial No. 665,935

11 Claims. (Cl. 105—228)

My invention relates to improvements in underframe construction for railway cars.

This invention has particular reference to the construction of railway car underframes and has for one of its objects the provision of an improved combination casting which will act as a foundation member for the centersills and bolster sections and operate to provide a rigid connection for the parts, this application forming a continuation in part of my pending application Serial Number 601,123, filed March 25th, 1932.

Another object of my invention is to provide an improved foundation bolster casting constructed in such a manner as to minimize the strains on riveted connections by providing more adequate and direct contact between the car parts and said casting, than has heretofore been possible with existing structures.

Still another object of my invention is to provide a foundation casting in which the parts are so formed as to facilitate manufacture and reduce finishing operations on said castings to a minimum.

Still another object of my invention is to provide a foundation bolster casting having riveted connections so disposed as to facilitate assembly of the car parts by disposing the rivet connections in locations which will be readily accessible to the riveter.

My invention also provides for a combined center plate and buffing casting member so constructed as to be braced in both horizontal and vertical directions and also longitudinally and transversely of the car to adequately resist shocks due to buffing impact and vertical loading on the center plate.

A still further object of my invention is to provide a foundation bolster casting which will completely fill the space intermediate the centersills and thereby prevent inward crushing of the centersills due to the vertical strains imparted thereto by the bolster and to also strengthen the casting above the center plate for preventing bending of the center plate and of the bolster bottom tie member due to strains brought about by the functioning of the latter as a compression element of the bolster.

Another and still more specific object of my invention is to provide a foundation bolster casting member adapted to cooperate with a centersill structure of generally box-shaped construction whereby a portion of the foundation casting may be extended lengthwise of the centersills and in the plane of and above the lower horizontal wall means of the box-shaped centersill.

My invention further resides in certain detail of parts and improvements such as will be more fully pointed out hereinafter.

For further comprehension of my invention reference may be had to the accompanying drawings wherein:

Fig. 1 is a vertical transverse sectional view taken through the lower portion of a railway car adjacent one of the trucks and bolster parts, and incorporating my improved foundation bolster member, certain parts of the bolster diaphragms being broken away to better illustrate the construction;

Fig. 2 is a top plan view of that part of the car illustrated in Fig. 1, said view illustrating the bolster top cover plate removed and certain parts broken away to better illustrate the construction;

Fig. 3 is a bottom plan view of the body bolster construction illustrated in Fig. 1;

Fig. 4 is a longitudinal vertical sectional view on an enlarged scale taken on a line corresponding substantially to a line 4—4 of Fig. 2;

Fig. 5 is a transverse vertical sectional view on an enlarged scale taken on a line corresponding substantially to a line 5—5 of Fig. 2;

Fig. 6 is a fractional vertical sectional view on an enlarged scale taken on a line corresponding substantially to a line 6—6 of Fig. 2;

Fig. 7 is a fractional vertical sectional view taken on a line 7—7 of Fig. 6;

Fig. 8 is a vertical sectional view taken through a portion of the body bolster and on a line corresponding substantially to a line 8—8 of Fig. 6;

Fig. 9 is a vertical transverse sectional view taken through the lower portion of a car illustrating the application of my improved construction to a car having a modified form of centersill construction wherein the centersill beam members have integral inner and outer lower marginal flanges;

Fig. 10 is a vertical transverse sectional view taken on a line 10—10 of Fig. 9;

Fig. 11 is a top plan view of Fig. 9, certain parts being broken away;

Fig. 12 is a bottom plan view of that part of a car illustrated in Fig. 9;

Fig. 13 is a fractional vertical transverse sectional view on an enlarged scale of the center portion of my improved foundation bolster as shown in Fig. 9, except that the construction is modified to incorporate centersills which are of built-up construction instead of integral beam members;

Fig. 14 is a longitudinal vertical sectional view of the rear portion of the foundation bolster casting illustrated in Fig. 13, said view being taken on a line corresponding substantially to a line 14-14 of Fig. 13;

Fig. 15 is a sectional plan view corresponding substantially to a line 15-15 of Fig. 14;

Fig. 16 is a vertical transverse sectional elevational view showing my improvements applied to a car construction having a single web bolster construction of the type usually incorporated in hopper cars;

Fig. 17 is a sectional top plan view of the construction illustrated in Fig. 16;

Fig. 18 is a bottom plan view of that part of the car illustrated in Fig. 16;

Fig. 19 is a vertical longitudinal sectional view on an enlarged scale taken on a line 19-19 of Fig. 16;

Fig. 20 is a fractional transverse vertical sectional view taken through the centersills and on a line corresponding substantially to a line 20-20 of Fig. 19;

Fig. 21 is a vertical transverse sectional view taken through the lower portion of a hopper car illustrating my improved construction in a modified form wherein the horizontal lower wall of the centersill is composed of a bottom tie plate which with my improved foundation bolster casting forms a composite tie construction across the plane of the centersills for the bolster bottom tie member;

Fig. 22 is a vertical transverse sectional view on an enlarged scale taken on a line 22-22 of Fig. 21;

Fig. 23 is a vertical transverse sectional view on an enlarged scale taken on a line corresponding substantially to a line 23-23 of Fig. 21;

Fig. 24 is a view of the bolster bottom tie plate employed in connection with my improved foundation bolster casting, said plate being shown in detached relation.

In said drawings the truck parts are generally indicated by the reference character A and the body portion of the car at B. The truck parts A are shown as including the wheels 10 and truck side frames 11, the latter including journal boxes 12. The usual truck bolster is indicated at 13, said bolster having side bearings at 14-14 and the center plate bearing portion at 15.

The car body construction B includes a longitudinally extending centersill structure 16 formed of a pair of beam members 17 arranged with their webs 18 vertically disposed. Said Z-shaped members are preferably formed of Z-shaped section with their respective upper flanges 19-19 inwardly directed toward each other and preferably united at their meeting edges along the longitudinal center of the car by welding as indicated at 20. The lower flanges 21 of each Z-member 17 face horizontally outwardly of the centersill structure.

Spaced outwardly from said centersill structure are the car side walls 22-22, and extending transversely of the car on each side of the centersill between the center and side walls are the bolster diaphragms 23-23; said bolster diaphragms being arranged in pairs on each side of the centersill and spaced from each other lengthwise of the car an appreciable distance.

Each diaphragm 23 is preferably of pan-shaped formation with an upstanding web section 24 and a continuous marginal outstanding

flange presenting upper and lower flanges 25 and 26 respectively, also inner and outer vertical flanges 27 and 28; said inner and outer flanges being adapted to respectively overlie and connect with the centersill webs and side sills of the car. Extending transversely of the car from side to side thereof is the bolster top cover plate member 29 which is riveted to the upper flanges 25-25 of the respective diaphragms 23 thereby providing an upper tension member for the bolster construction.

The compression element of the bolster includes my improved foundation bolster casting C which is preferably formed of cast steel and includes a flat body portion 30 which extends flatwise continuously across the centersills and beneath the bolster sections or diaphragms 23-23 on the respective sides of the centersills and is united therewith by a series of rivets 31. The member C has formed integrally therewith a depressed center plate portion 32 which cooperates with the center plate section 15 of the truck bolster and which includes a cylindrically shaped section having a substantially vertical wall 33.

Extending up above the flat body portion the foundation member is formed with an upstanding integral spacing portion 34 having two substantially parallel vertical walls 35-35 which overlie and are riveted to the respective webs 18-18 of the centersill structure by rivets 35a. The walls 35-35 are extended lengthwise of the car for an appreciable distance beyond the flat body portion 30. Said walls 35-35 are transversely united by a series of transversely extending walls as indicated at 36, 37, 38, and 39, respectively. The wall 36 which is disposed at the forward end of the foundation bolster member constitutes a rear draft rigging abutment wall for the draft rigging parts 40. The said wall 36 extends vertically for a distance corresponding approximately to the depth of the draft yoke 41. The lower portion of the wall 36 is spaced an appreciable distance above the flat wall portion 39 and each of the transverse walls 37 and 39 is preferably disposed in substantial alignment with the webs 24 of the bolster sections 23 and constitute diaphragms adapted to fill substantially the entire space between the centersills. Each of said walls 37 and 39 is provided with a horizontally extending upper wall 42 which underlies the upper wall of the centersill beams and is riveted thereto by means of rivets 43 which extend through the said horizontal wall, the top centersill flanges and bolster top cover plate. The said horizontal wall 42 is provided with an elongated raised boss 44 through which the rivets 43 extend, said boss forming a bearing pad which may be readily machined or ground to provide the required height of casting without the necessity of machining the entire area of top wall.

The respective walls 37 and 39 are united lengthwise of the car adjacent the centersill webs by longitudinal vertical walls 45-45 which are spaced transversely inwardly a slight distance from the centersill flanges and also from the bearing surfaces of the walls 35-35. The walls 37, 39 and 45 in effect provide a rectangular box-shaped section which is disposed substantially in alignment with the outermost portion of the cylindrical contour 33 of the center plate section thereby providing beams of considerable depth above and adjacent the center plate portion, whereby bearing strains from the center

plate are transmitted to the upper wall of the centersills.

The central portion of the foundation member is provided with an upstanding tubular shaped formation 46 which extends upwardly to a location slightly above the center line of draft 47. Said tubular formation 46 is respectively braced relatively to the transverse diaphragm walls 37, 39 and longitudinal side walls 45-45 by means of the transverse vertical wall 38 and longitudinal vertical walls 48-48; said walls 38 and 48 being disposed at right angles to each other across the center plate thereby presenting a cross-shaped structure to reinforce the body of the center plate intermediate the walls of the cylindrical contour 33. Intermediate the draft abutment wall 36 and the diaphragms 37 there is formed a vertical wall 49 which is disposed substantially in alignment with wall 48 and extends from the upper wall 42 to the lower horizontal wall of member 30. The abutment wall 36 is braced rearwardly to the longitudinal walls 35-35 by means of horizontal walls 50 and 51; said walls 50 and 51 being disposed on opposite sides of the draft line 47. The wall 50 is disposed on the lower side of the draft line and extends from a location slightly above the lower portion of the draft abutment wall 36 to the adjacent diaphragm wall 37, said wall 50 being provided with a pair of openings as indicated at 52 whereby ready access is permitted to the connecting rivets between the walls 35 and the centersill webs. The wall 51 is disposed above the draft line and slightly below the top of the wall 36 and extends an appreciable distance rearwardly of the said abutment wall and merges into the longitudinal vertical walls 35 and 49 and is united therewith by means of substantial radii as indicated at 53.

Intermediate the diaphragms 37 and 39 and the longitudinal side walls 45-45 there is disposed a horizontal wall 54 which encircles the thimble portion 46 and is in effect a continuation of wall 50 and serves to distribute buffing strains from the forward end to the more remote parts of the casting. The horizontal wall 54 further serves to strengthen the casting and increase the efficiency of the foundation casting member as a centersill spacer.

The flat body portion 30 is provided with integral side bearing portions 55-55 on each side of the centersills, and above said side bearings there are provided upwardly extending integral portions 56 each provided with walls 57-57 which overlie and are riveted to the upstanding webs 24 of the pair of bolster sections 23 by rivets 58. The walls 57 are spaced slightly from the webs by means of triangular shaped bosses 59 which provide raised surfaces at the ends of the extensions, said raised surfaces being spaced above the main body portion 30 thereby facilitating machining of the castings to insure a proper fit between the bolster diaphragms 24 and the foundation body bolster member. The ends of the body portions 30 outwardly of the side bearings are depressed as indicated at 60. Sandwiched between said depressed portions and the bottom flanges 26 of the bolster diaphragms is a plate member 61 which is riveted as indicated at 62, and also welded to the member C as indicated at 63. Each plate 61 extends outwardly to the side sill of the car and is united therewith and with the bolster diaphragm bottom flanges 26 by a series of rivets 64. The member C is reinforced transversely of the car by depending

flanges 65, the depth of which are graduated from a maximum adjacent the centersills of the car to a minimum adjacent its outer ends. The depending flanges 65 are disposed outwardly beyond the center plate section and in effect provide a channel shape section extending transversely of the car beneath the bolsters.

The body portions 30 are further braced transversely and longitudinally of the car by shallow horizontal ribs 66. Outwardly of the depending flanges 65 the body portion 30 is extended lengthwise of the car as indicated at 67 by the provision of horizontal walls 68 which connect with the vertical walls 35 and which are riveted to the outstanding flanges of the centersills by means of rivets 69. The walls 68 are further braced to the depending flanges 65 by means of vertical gusset extensions as indicated at 70.

The upstanding center portion adjacent the bottom of the centersill is formed with an inset 20 in the form of a groove indicated at 71 extending lengthwise of the car, said groove being of a depth corresponding substantially to the extent of the set-backs of walls 45. The grooves 71, in cooperation with the set-backs of the walls 45, 25 provide in effect raised portions 72 which represent the surfaces against which the centersill webs bear when said centersills are in assembled relation with the foundation bolster casting. The use of raised surfaces in the manner indicated 30 reduces the extent of surfacing necessary on the casting to obtain flat bearing.

The underlying flat portion 30 intermediate the lower centersill flange 21 and the lower marginal flange 26 of the bolster sections 23, is formed with a depressed portion 73, said depressed portion 73 having the effect of providing slightly elevated surfaces at the outer portions of the underlying surfaces 30 as best indicated in Fig. 8, said raised surfaces being indicated at 74. Due to 40 the elevation of the surfaces as mentioned, it is possible to grind burrs and other obstructions on such raised surfaces without the necessity of guiding the entire face of the casting.

The flat portion 30 on each side of the centersills intermediate the side bearings, bolsters and centersills, is provided with an opening 75 having a beading 76 around its marginal edges; said openings 75 serve the purpose of lightening the casting, preventing shrinkage cracks in the 50 large flat areas presented by the section 30 and enabling access to the interior of the bolster to permit the use of rivets 77, said rivets 77 being for the purpose of uniting the flat portion 30 to the lower centersill flanges 21.

The extension of the casting upwardly a sufficient distance to abut the upper portion of the centersills, and thereby obtain bearing contact at the upper portion of the centersills as well as at the lower flanges of the centersills, takes care 60 of vertical loading on the center plate and enables the full strength of the rivets connecting the foundation bolster and centersills to be utilized to resist draft and buffing strains.

The bracing of the buffing casting, by employing an intersecting arrangement of walls leading from the rear abutment wall to the top, sides and bottom of the centersills, permits a uniform distribution of buffing strains to the centersills. In a construction of bolster such as illustrated in Fig. 70 1, a large proportion of the weight of the load and car body intermediate the trucks is carried by the sides of the car and transferred to the center-plate through the body bolster, thereby calling for the placement of considerable load on the ends 75.

of the body bolsters and transferring such loading from the ends of the body bolsters to the center plate. The bolster sections on each side of the centersills function as cantilevers, pivoting from a location adjacent the upper portion of the centersills and thereby placing the lower portion of the center filler casting in compression.

In bolsters of the identified construction it has heretofore been found that there has been an upward bending of the bottom tie member and center plate at the center of the car with a consequent upward displacement of the usual centersill filler casting, thereby ultimately resulting in the downwardly bending of the ends of the bolsters. My improved construction overcomes such weaknesses by utilizing a one-piece member between the centersills which completely fills the space between said centersills and makes direct contact with the upper and lower portion of the centersill and further provides strong diaphragms between the center sills which are disposed in alignment with the bolster sections on each side of the centersills.

In the modification shown in Figs. 9 to 12, inclusive, my improvements are shown as applied to a centersill construction having inner and outer integral outstanding flanges at the lower margins of the centersills, said inner flanges, in combination with the webs and upper horizontal top cover, defining a substantially box-like structure. My invention is modified to facilitate the application or removal of such a casting from the car when the car parts are in assembled relation. In said figures of the drawings, the truck is indicated at 100 and the body of the car at 101. The center-sill construction is indicated at 102 and includes a pair of vertical beam members 103—103, each of which includes vertical web sections which have outwardly extending top flanges 105, and inner and outer outstanding lower marginal flanges 106 and 107, respectively. The outer flanges 107 extend continuously past the body bolster, and the inner flanges 106 are cut away rearwardly of the body bolsters as indicated at 108. On each side of the centersill are the bolster sections 109, each having a vertical web 110.

The foundation bolster member D has an underlying flat portion 111 extending transversely across the plane of the centersill below the bolster sections 109—109. The member D is also provided with an upstanding portion 112 which extends to the upper portion of the centersill and bears against the underside of the bolster top cover plate 113 and is riveted thereto by means of rivets 114. The construction of the forward part of the foundation bolster casting or that part of the casting having the abutment walls, in so far as the intersecting walls and diaphragms are concerned, corresponds substantially to the disclosure of Figs. 1 to 8 inclusive. The rearward portion of the casting includes a flat horizontal extension 115 which projects beyond the flatwise portion 111 and is secured to both the inner and outer flanges of the centersills as indicated at 116 and 117 respectively. The flatwise portion 111 of the casting is braced across the plane of the centersills by the depending flange 118, and said flat rearward extension 115 is braced beneath the sills and at the center of the car relatively to the depending flanges 118 by a vertically extending flange 119. The upstanding portion 112 is provided with side walls 120—120 which attach to the vertical webs 104 of the centersills, and each of said walls at the rear end

of the casting is formed with a portion 121 which extends for an appreciable distance beyond the cut-away ends 108 of the inner flange 106 of the centersills and is riveted to the said centersills by rivets 122. The portion 121 commences at an appreciable distance above the lower flange of the centersills, thereby permitting the casting D to be lowered vertically a distance corresponding to the dimension 123 without interference with the lower inner flanges of the centersills. The bolster bottom member D is provided with side bearings 124, and above each side bearing there are provided bracket portions 125 so arranged as to space the bolster diaphragms and maintain said diaphragms in spaced relation. Each bracket 125 includes walls 126 arranged in overlying relation with the bolster diaphragms; said walls 126—126 are extended lengthwise of the bolster diaphragms beyond the side bearings and are provided with raised portions 127 constituting bearing pads. The bracket portions 125 are so limited in height that when the casting D is lowered a distance corresponding to the dimension 123 (Fig. 10), the said brackets 125 will clear the lower portions of the diaphragms and the casting can then be moved forward a sufficient distance to enable the walls 121 to clear the end of the inner flanges of the centersills 106. Thus the casting may be removed from the car or applied without the necessity of dismantling the bolster and centersill construction.

The construction shown in Figs. 13 to 15, inclusive, indicates the modifications necessary in the casting and related construction when the centersills are of built-up construction instead of having the flanges integral with the web sections as described in Figs. 9 to 12, inclusive, and only the rear end of the casting is shown. In said Figs. 13 to 15, inclusive, the centersill structure as shown is formed of two vertically disposed web sections 200, outer top angle 201, inner and outer bottom angles 202 and 203, respectively. The outer angle is formed to extend continuously past the body bolster and terminates adjacent the bolster. The inner and outer angles are each formed with an outstanding lower marginal flange 204 and 205, respectively. The foundation bolster casting which is indicated at E is formed with an upstanding portion 206 which includes vertical side walls 207—207, united transversely of the car by walls 208, one of which is shown. The wall 208 is provided at the top with a wall 209 which extends horizontally and bears against the centersill top cover plate, the latter being indicated at 210. The longitudinal walls 207 of the casting, at the rear end, terminate adjacent the end of the inner bottom angle of the centersill, and the space intermediate the wall 205 and bottom angle is bridged by an underlying wall portion 211 which is braced above and below by gusset portions 212 and 213, the former being braced relatively to the upstanding wall 208 of the diaphragm section and the latter being braced relatively to a depending transversely extending wall 214. The said underlying portion 211 is riveted to the outstanding flanges 204 and 205 of the centersill by means of rivets 215.

In the modifications shown in Figs. 16 to 20, inclusive, my improvements are shown as applied to a type of car having a bolster of single web section such as is commonly employed in connection with cars having deep bolsters as in hopper cars having sloping end walls. In said drawings the truck parts are indicated at F and the body of the car at G.

The centersill construction includes two Z-shaped members 300—300 extending longitudinally of the car, and above and to each side of the centersills is a vertical web plate 301 which is formed with a cut-away portion 302 enabling the plate to straddle the centersills. The plate is extended outwardly towards each side wall of the car 303 and is suitably connected therewith by means of angles 304 or other suitable connecting means. The side walls of the car are reinforced at their lower margins by longitudinal extending angles 305; the lower margin of the web plate 301 of the bolster being reinforced by angles 306 which are disposed on opposite sides of the web plates and extend from the side of the car to the centersills, each said angle being arranged with one flange 307 vertically disposed and having the adjacent flange 308 extending substantially horizontally. The web plate is united to the centersills by means of vertically disposed angle-shaped connections 309 and 310, the former extending substantially to the full depth of the centersill web and the latter being extended above the centersill and to substantially the top of the bolster. The bolster sections on the opposite sides of the centersills are united at their lower ends by means of the foundation bolster casting H which includes a lower flat portion 311 and an upstanding portion 312, the latter extending between the centersills and bearing against the underside of the upper portion of the centersills. The lower flat portion 311 includes on its underside the center plate section 313 formed integrally therewith and also integral side bearing portions 314—314. The said flat portion is reinforced transversely of the car adjacent its edges by means of depending flanges 315. The upstanding portion 312 includes side walls 316—316 formed at one end with draft abutment portions 317 against which the draft rigging 318 is adapted to abut. The construction shown on the drawings at the draft end of the casting is adapted to meet the requirements of a vertically disposed yoke, but it will be understood that said construction at the end which cooperates with the draft attachments may be modified for the use of a different type of yoke or draft attachment without departing from the spirit of my invention.

The respective side walls 316—316 are united transversely of the car by a horizontal upper wall 319 and transverse vertical walls 320 and 321—321. The walls 321 extend for the full depth of the centersill from the outermost portion of the horizontal wall 320 to the lower flat portion 311 and cooperate with the said top and bottom flat walls and the vertical side walls 316—316 to form a six-sided box-shaped section which completely fills the space between the centersills. The walls 321—321 are formed with openings 322 to permit access to rivets 323, and the respective vertical walls 316 and 321 are braced relatively to each other by integral ribs 324 and 325. The transverse vertical wall 320 completely fills the space intermediate the vertical and upper walls and is disposed in substantial alignment with the vertical web plate 301 of the bolster. The center portion of the casting intermediate walls 321—321 is reinforced lengthwise of the car by means of vertical walls 326 which in cooperation with walls 320 define a cross-shaped reinforcement around the vertical thimble portion 327 of the casting. The bracing effect of walls 326 is continued beyond walls 321 by means of gusset portion 328 which brace the overhanging portions of the lower

flat plate portion 311 of the foundation bolster casting.

The upper horizontal wall 319, through the medium of raised elongated bosses 329, bears against the top flange of the centersill. Extending transversely of the centersill and above the same is an angle-shaped member 330 which has one flange 331 vertically disposed and secured to the bolster web. The adjacent flange 332 extends horizontally and rests on the top of the centersill. The said angle member is extended downwardly on each side of the centersill towards the side bearings 314 and adjacent the latter is united through the medium of braces 332 to the bolster bottom angles 308 and to the tie portion of the foundation member H. The upstanding portion 312 of the foundation casting thus provides a direct support for the angle-shaped member 330, and said portion 312 acts as the strut of a truss construction between the side bearings and center plate wherein the angle member 330 is one of the members and the flat portion 311 of the foundation casting one of the other members of the truss.

In the construction shown in Figs. 21 to 24, inclusive, my construction is shown as of a composite construction wherein the casting is formed of reduced size and functions as a tie member in cooperation with a commercially rolled plate.

In said construction the centersill is formed of a pair of Z-shaped members 400—400 and on each side of the centersills is a pair of bolster diaphragms 401—401 which extend from the centersills to the car side walls 402. The bolster diaphragms are united at their upper portion by a tie plate 403 which extends from side to side of the car. The bottom member or compression part of the bolster includes a foundation bolster casting J and a bottom tie plate 404. The said plate is best illustrated in Fig. 24 and is formed with a cut-away portion as indicated at 405, said cut-away portion being for the purpose of straddling the upper part of the foundation bolster casting when the parts are arranged in assembled relation as will be hereinafter described.

The foundation bolster casting J is formed with an upstanding portion 406 and a lower flat portion 407, the latter extending transversely of the car beneath the center sills 400, bolster tie plate 404 and bolster diaphragms 401. In this embodiment of my invention the main portion of the upstanding portion 406 of the foundation bolster casting is substantially similar to that described in connection with the embodiment shown in Figs. 1 to 4, inclusive, and includes side walls 408 and a front draft abutment portion 409, transverse walls 410—410, the latter extending between the centersill webs and disposed substantially in alignment with the bolster diaphragms. At the rear end of the casting the side walls 408 are separated at the lower portion of the casting from the underlying flat portion 407 for the purpose of providing a recess as indicated at 411, said recess being for the purpose of accommodating the plate 404 between the side walls 408 and lower flat portion of the casting 407. In this embodiment of my invention, the bottom cover plate 404 is extended continuously between the car sides 402 and united therewith, and the flat portion 407 of the foundation bolster casting J terminates adjacent to the side bearings 412, said side bearings being spaced from and mounted independently

of the foundation bolster casting. The bolster diaphragms above the side bearings are braced by the usual side bearing braces 413 which serve the purpose of spacing the bolster diaphragms 5 and providing adequate reinforcement above the side bearings. In this embodiment of my invention, the foundation bolster casting proper and the tie plate 404 are united together by means of rivets 414 before application to the car and 10 the assembled structure can then be applied on the car in assembled relation. In order to further unite the parts and cause the plates 404 and foundation bolster casting to function as a unitary structure the parts are welded together 15 as indicated at 415 and 416.

As will be noted by reference to Fig. 22, the plate 404 provides a rearward flat extension for the underlying flat portion 407 of the foundation bolster casting corresponding to the integral construction described in connection with certain of the previously described constructions. Said plate 404 may be extended rearwardly of the foundation bolster casting a greater distance than shown on drawings, but in any event a 20 plate as indicated provides a box-shaped centersill structure within which a portion of the foundation bolster is extended.

I claim:

1. In an underframe for railway cars, having a centersill including spaced vertical walls each provided adjacent the lower margin with an outstanding marginal flange and adjacent the upper margin with inwardly directed flanges; a foundation bolster casting positioned between the 30 said vertical walls of the center sill and having integral portions bearing on both the upper and lower flanges of the centersill and united therewith and with the vertical walls of the centersill, said casting including in an integral unit a center plate section and a draft abutment.
2. In an underframe for railway cars including a centersill formed of two Z-shaped sections disposed with their upper flanges inwardly directed and having the lower flanges extending outwardly, and bolster sections on each side of the centersills; a foundation bolster casting having 40 an integral underlying portion bearing on the lower flanges of the centersill and extending transversely of the car beneath the bolster sections and attached thereto, said casting having an integral portion extended upwardly between the centersills and provided with a bearing against the upper flanges of the centersills.
3. In an underframe for railways cars, said underframe including a centersill having a pair of vertical web plates spaced apart and an upper horizontal wall connecting said vertical web plates, bolster sections extending transversely of the car on each side of the centersill, said bolster sections each including a vertical web and arranged in pairs on each side of the centersill, said respective sections of a pair being spaced from each other lengthwise of the car; a foundation bolster casting having an underlying plate portion 50 adapted to extend beneath the centersills and the bolster sections, said casting having integral diaphragm portions extending upwardly between the centersills and disposed substantially in alignment with the bolster sections, each said diaphragm including an upper horizontal wall adapted to underlie and be united with the upper horizontal wall of the centersills.
4. In an underframe for railway cars, said underframe including a centersill having a pair of 75 vertical web plates spaced apart and an upper

horizontal wall section connecting said vertical walls; bolster sections disposed on the opposite sides of the centersills and extending transversely of the car, said bolster sections being arranged in pairs on each side of the centersills and each including a vertical web; a foundation bolster casting having an underlying plate like portion adapted to extend beneath the centersills and bolster sections, said casting having an upwardly extending integral portion positioned between the centersills, said upward extension having transversely extending webs disposed substantially in alignment with the respective bolster sections and extending between the respective centersill webs, each said transverse wall of the casting having an upper horizontal wall adapted to underlie and be secured to the upper horizontal wall of the centersills.

5. In an underframe for railway cars, the combination with the centersills including vertical webs and bolster sections on each side of the center sills, said bolster sections being spaced from each other lengthwise of the car; a foundation bolster casting having an integral bottom cover plate extending transversely of the car beneath the centersills, said cover plate including an integral center plate portion, and said casting having upwardly extending diaphragm portions disposed between the centersills, and spaced from each other and lying substantially in alignment with the bolster sections, said upwardly extending diaphragm portions being united lengthwise of the car by longitudinal extending walls spaced slightly from the centersill webs.

6. In a railway car underframe having centersills extending lengthwise of the car and including a pair of upstanding web portions; a bolster structure on the opposite sides of the centersills; a bolster foundation casting having an upstanding portion lying between the centersill webs and having a body portion extending flatwise beneath the centersills and extended outwardly beneath the bolster structure on each side of the centersill and united therewith, said flat body portion having a center plate portion formed integral therewith, said center plate having a circular wall contour of appreciable depth, said upstanding body portion of the foundation bolster casting including longitudinally extending vertical walls disposed adjacent the centersill webs and a series 50 of transversely extending walls connecting said longitudinal walls, one of said transverse walls being disposed centrally of the centerplate and the others being respectively disposed substantially in alignment with the outermost contour 55 of the center plate; and a longitudinally extending vertical wall centrally disposed between the centersills adapted to intersect said series of transverse walls and be integrally united with the flat portion of the bottom member.

7. In a railway car underframe construction, the combination with longitudinal centersills defined by vertical webs spaced apart and an upper horizontal wall section forming with the said webs an inverted U-shaped construction; of a combined center plate, centersill filler and draft rigging backstop positioned within the said centersills and having walls secured to the said webs of the centersill; said member including an integral center plate portion constituting the bottom 70 wall of the casting, and having a dished portion presenting vertical walls extending in a circular contour; integral reinforcing walls above the center plate portion extending transversely and longitudinally of the car, said transverse and 75

longitudinal reinforcing walls cooperating to form a four-sided box-shaped section, and being disposed above the outermost portion of the vertical walls of the center plate portion, and other 5 bracing webs extending vertically across the center plate portion transversely and longitudinally of the car to provide an integral cross-shaped reinforcement above the intermediate portions of the center plate portion.

10 8. In an underframe for railway cars, the combination with longitudinal centersills defined by vertical webs spaced apart and an upper horizontal wall section forming with the said webs an inverted U-shaped construction; of a combined 15 center plate, centersill filler and draft stop casting positioned within the said centersills, said casting having longitudinal walls overlying and secured to the webs of the centersill, said casting including an integral center plate portion forming 20 a portion of the bottom wall of the casting, said center plate having a dished portion presenting vertical walls extending in a circular contour, integral vertical walls extending transversely of the car above the center plate, said transverse 25 walls being disposed substantially in alignment with the outermost portion of the vertical walls in the center plate circular contour, and extended upwardly to the upper portion of the centersill and there formed with a horizontally extending 30 wall bearing against the upper horizontal wall of the centersill, whereby center plate bearing strains are transmitted directly from the center plate to the upper wall of the centersill.

9. As an article of manufacture, a foundation 35 bolster casting having an upper portion adapted to be positioned between the walls of a centersill, said casting having on each side of the centersill an integral bottom plate portion extending beneath the centersills and beyond the same for 40 attachment with bolster members, said upper portion having a transverse vertical wall located an appreciable distance from the plate-like portion and constituting a draft stop; and reinforcing means extending from the draft stop to the 45 bottom plate section, said means including a vertical wall formed integrally with the said bottom cover plate and draft stop wall, said wall being located centrally between the centersill

walls and extending for substantially the entire depth of the centersills.

10. As an article of manufacture, a foundation bolster casting adapted to be positioned between the walls of a centersill, said casting having an integral flat wall portion constituting a bottom tie plate extending beneath the centersills and beyond the same for attachment with bolster sections on each side of the centersill; a transversely extending vertical wall spaced appreciably lengthwise of the car beyond the tie plate and disposed above said tie plate portion and constituting a draft buffering wall; reinforcing means extending from the buffering wall to the bottom tie plate section; said means including a longitudinally extending centrally disposed vertical wall formed integrally with the said bottom tie plate and buffering wall; and other bracing means adapted to brace the said vertical wall and draft stop wall including a horizontal wall disposed to 15 intersect the said vertical wall in the plane of the buffering wall. 20

11. In an underframe for railway cars, having a centersill including spaced vertical walls and an upper horizontal wall connecting said vertical walls; a foundation bolster casting positioned between the said vertical walls of the centersills, said casting having longitudinal vertical walls overlying the centersill webs and secured thereto, transverse vertical walls uniting the said longitudinal walls, an upper wall bearing against the upper wall of the centersill and a flat portion extending flatwise beneath the centersills and having an integral center plate formed therewith, one of the said transverse walls being disposed forwardly of the center plate and constituting an abutment for draft rigging, a plurality of horizontal walls extending rearwardly of the said vertical buffering wall and united to the longitudinal vertical walls, said horizontal walls being respectively disposed adjacent the upper and lower margins of the buffering walls and a centrally disposed vertical wall disposed inwardly of the buffering wall and extending from top to bottom of the casting and merging into the respective upper and lower horizontal walls of the casting. 25

ARGYLE CAMPBELL.
